CLAIM

The ornamental design for a shoulder rest for telephone handset, as shown.

DESCRIPTION

FIG. 1 is a front, top and right side perspective view of a shoulder rest for a telephone handset showing our new design;

FIG. 2 is a right side elevational view thereof, the side opposite being a mirror image;

FIGS. 3 and 4 are respectively rear and front end elevational views thereof; and

FIGS. 5 and 6 are respectively top and bottom plan views thereof.
